UNITED STATES PATENT OFFICE.

EUSTACE CREEES AND CHARLES S. COURT, OF PROVIDENCE, RHODE ISLAND,
ASSIGNORS TO THE WATSON AND NEWELL COMPANY, A CORPORATION
OF RHODE ISLAND.

DESIGN FOR A HANDLE FOR SPOONS OR SIMILAR ARTICLES.

SPECIFICATION forming part of Design No. 36,220, dated February 10, 1903.

Application filed January 9, 1903. Serial No. 138,444. Term of patent 3½ years

To all whom it may concern:

Be it known that we, EUSTACE CREEES and CHARLES S. COURT, citizens of the United States, residing at Providence, in the county of Providence and State of Rhode Island, have invented and produced a certain new, original, and ornamental Design for the Handle of a Spoon or Similar Article, of which the following is a specification, reference being had to the accompanying drawings, forming part thereof.

Figure 1 is a view of the obverse side of a spoon-handle, showing our new design; and Fig. 2 the reverse side of the same.

The leading feature of our design consists in the representation, in relief, of the needles and cones of the pine-tree arranged into an ornamental design for a handle.

In the drawings, A is the head, and B the shank, of the handle. On the obverse side, Fig. 1, the marginal lines 3 3 form the outermost edges of the handle. At the narrow part of the shank B the surface 4 between the lines 3 3 is corrugated and rasp-like, representing the bark of a tree. The upper and wider portion of the shank is ornamented with clusters of needles 5 5 and cones 6 6, which spring from the marginal lines 3 3 and twine upward into the head A. Within the head A the needles 7 7 and cones 8 8 form a wreath around a plain center C. At the upper extremity of the head A is a cluster of needles 9, forming a semicircular apex to the handle, beneath

which is suspended the cone 10. Across the base of the handle lies a cluster of needles 11. 35 On the reverse side, Fig. 2, the edge of the handle is defined by the marginal lines 3 3, whose surfaces are corrugated and rasp-like, representing the bark of a tree. At the junction of the head A with the shank B radiations 4 4 from the lines 3 3 cross each other to the opposite side and at their point of intersection support a cluster of needles 5. At various points along the lines 3 3 spring the needles 6 and cones 7. The semicircular apex 45 at the upper extremity of the head contains a cone 8. At the base of the handle lies a sprig of the pine-tree, with needles 9 9 and cone 10.

It is evident that our design is applicable 50 to the handles of articles other than but similar to spoons.

Having described our invention, what we claim as new, and desire to secure by Letters Patent, is—

The ornamental design for the handle of a spoon or similar article, as herein shown and described.

In testimony whereof we have affixed our signatures in the presence of two witnesses. 60

EUSTACE CREEES.
CHARLES S. COURT.
